UNITED STATES PATENT OFFICE

2,346,390

MEANS FOR HANDLING CONTINUOUS
MANIFOLDING PAPER

William C. Pfeiffer, Dayton, Ohio, assignor to The
Egry Register Company, Dayton, Ohio, a corpora-
tion of Ohio

Application December 26, 1941, Serial No. 424,452

7 Claims. (Cl. 197—126)

The object of my invention is to provide a means and method of handling continuous form stationery with interleaved carbons, and particularly interleaved carbons that correspond approximately to the length of two forms and which can be used repeatedly between successive forms.

It is the object of the invention to provide a means of positioning such carbon sheets automatically between the paper sheets, so as to permit of the duplicate writing of messages on successive forms, using the same carbon sheets between the successive forms.

In particular it is the object of my invention to do this in connection with business machines, such as typewriters and the like.

It is the object of this invention to provide an apparatus which will support and feed a plurality of paper strips constituting continuous form stationery around the typewriter platen, or the like, with a group of interleaved carbon paper sheets; and after the message has been written, the combined paper and carbon sheets are returned to their initial position before writing; and thereupon the carbon sheets are held against forward movement temporarily while the written upon paper sheets comprising one form are again moved over the platen to tear off position and are torn off with the next succeeding set of forms, which have not been written upon, positioned for the new writing operation with the carbon sheets therebetween so that the carbon sheets and the new paper sheet forms may proceed through another writing cycle.

It is a further object to provide an attachment for a business machine, such as a typewriter, which will guide the paper and carbon sheets into and out of writing position, and which will, at appropriate intervals, hold the carbon sheets from forward movement during the forward movement of the paper sheets.

It is a further object to provide guides on said mechanism which serve to maintain the paper sheets with their forms in alignment.

It is a further object to provide such a mechanism that can be raised and lowered and actuated for holding the carbon sheets or releasing them by a single movement of the operator's hand.

It is an object to provide such a mechanism that is so light in weight, that it does not impede or affect the normal operation of the typewriter carriage.

Referring to the drawings:

Figure 1 is a front elevation of the mechanism in its elevated position without paper or carbon;

Figure 2 is a side elevation of the mechanism

in its elevated position on the typewriter without paper or carbon;

Figure 3 is a similar view with the mechanism in its lowered position;

5 Figure 4 is a side elevation thereof;

Figure 5 is a top plan view partially broken away showing the interleaved arrangement of the paper sheets and the carbon sheets;

Figure 6 is a section taken longitudinally 10 through the carbon sheets and the paper sheets showing the interleaved arrangement;

Figure 7 is a perspective of the assembly of carbon sheets and supporting strips.

Figure 8 is a plan view of the continuous paper 15 sheets and carbon sheets with respect to their location to the typewriter platen at the four different stages of the operation of the apparatus and four stages of the method.

Referring to the drawings in detail:

20 1 is a typewriter or other business machine having a platen 2 with a knurled hand wheel 3 for rotating the platen. 4 indicates the writing point while 5 designates the carriage carrying the platen, such carriage having the back bars 6 and 7 on which are mounted side frame members 8 of a frame. This frame is further composed of a transverse bar 9 on which is mounted a guide 10. Optional members 11 to serve as stops may also be employed.

25 30 The frame just described is attached to the carriage by a latch finger 12 pivoted at 13 on the side frame members 8. This frame consisting of the side frame members 8, the interconnecting cross member 9 and the guide member 10 is provided with a tilting paper guide frame consisting of the side arms 14 which are provided on the side frame members 8 at 15. The outer ends of these side arms 14 are connected by the axle 16 on which is mounted a paper guide roll 17 and guide flanges 18. The flanges 18 are fixed to the axle 16 by set screws 19. The roller 17 freely turns upon the axle 16. The lower ends of the side frame members 14 are provided with levers 20 which are joined at the rear of the device by a rod 20'.

35 40 Attached to rod 20' and arranged to slide transversely thereon as the carriage of the machine is moved, is a pitman 21 which in turn is pivoted at 22 to a one arm 23 of a bell crank lever pivotally supported on the back of the typewriter 1 at 24. The other arm of the bell crank 25 is pivotally connected at 26 to a pitman 27 which is pivotally connected at 28 to one arm 29 of a bell crank pivoted at 30 and provided with another arm 31 having a finger piece 32. In this manner the pivoted frame 14 and associated parts

are raised and lowered. The pivoted frame 14 is provided with cross guides 33 and 34.

A carbon retaining latch is provided as follows. Pivoted links 35 and 36 are pivoted at their lower ends 37 on the side frame members 8. Their upper ends are connected at 38 to one arm of a bell crank 39. This bell crank consists of a wire wound around the axle 16 to form a loop at 40 and extending into a second arm 41 having a hook 42 on the outer end. This hook is in its retracted position when the frame members 14 and the members 35 constituting the pivoted frame mechanism are in their lowered position as shown in Figure 3.

The hook is advanced, however, when the frame is elevated as shown in Figure 2. The purpose of this hook, as hereinafter described is to engage the transverse carbon carrier plates to hold the carbons from moving after a writing operation has been performed and it is desired to move the paper sheets relative to the carbon sheets.

To this end, there are provided a plurality of superimposed paper sheets designated 43a, 43b, 43c, etc. It will be understood any number of such sheets may be employed. These sheets are divided by transverse perforations at 44 into a series of "forms" or "tickets" upon which are printed, ordinarily, various types of business forms which are usually identical.

Interleaved between the paper sheets adjacent the free ends of the paper sheets are the carbon sheets 45a, 45b, etc. Each of these sheets is attached to a transverse plate carrier 46a, 46b, etc. Such a carrier is usually of light material such as paste board, etc. These carriers are preferably attached together as by a staple 47.

The carbon sheets so carried are long enough to cover the areas of the printed forms of two adjacent tickets but they are not as long as the total length of the two tickets. The carbon sheets extend throughout the length of the last group of tickets which are being written upon in the typewriter and the next to the last group of tickets which are yet to be written upon but which are next in order of succession for that purpose. This arrangement is shown in Figure 5 particularly.

Operation

With the ends of the paper sheets in position with the top of the sheets just beyond the writing point 4 so that the top line of the form can be written upon, the ends of the carbon sheets are located slightly above this writing point extending backwardly throughout the length of the form or ticket being written upon and substantially throughout the length of the next succeeding ticket which will be next written upon.

As the paper sheets and carbons progress through the machine during the writing upon the first form and the making of carbon copies through the carbon sheets upon the underlying forms of the first set of tickets, eventually the operator comes to the end of the form.

Her problem is then to remove the carbon sheets simply and quickly without touching them and to position them between the paper sheets of the next succeeding form for another writing operation. She has the further problem of tearing off the written upon forms without tearing the carbons.

This problem is solved as follows by this invention. The operator reverses the platen backwardly the paper sheets with interleaved carbons backwardly until the carbon carrier 46a, 46b, 46c, etc., reaches a position above the hooks 42 which

are in their retracted position. Then the operator presses a finger piece 32 elevating the pivoted frame and bringing the hook 42 in advance of the carbon carrier 46a, 46b, etc., preventing any forward movement of the carbon sheets. While the carbon sheets are so locked in position, she again actuates the platen to move the paper sheets forwardly the length of the written upon tickets. In so doing, the written upon tickets are moved forwardly beyond the end of the carbon sheets which are held stationary. This is continued until the perforated line 44 known as the tear-off line is in position for tearing off the paper sheets which have been written upon and which are free from carbons. This leaves the free forward ends of the next adjacent set of forms or tickets in writing position with the carbons interleaved between them. The tilting frame or side arms 14, etc., are then lowered and when this is done the hook 42 is withdrawn releasing the carbon carrier so that the carbon sheets can progress through the machine with the paper sheets for writing upon the next set of forms on the next set of tickets.

It is understood that the paper sheets may be supplied from a zig-zag folded pack as illustrated or from rolls or in any other way that proves to be suitable.

It will be observed that the curved upper end of the stationary guide is useful when the pivoted frame is lowered to cause the paper and carbon sheets to bind and stay together without slipping as they move forward through the business machine. When the pivoted frame is lifted, the paper sheets and carbon sheets, which have been fastened together and which are to be independently moved in the opposite direction, are released from this binding action because these paper and carbon sheets are lifted from the curved stationary guide.

Furthermore, with the pivoted frame elevated you cannot move the paper sheets backwardly because their weight will cause them to buckle but you can move them forwardly while the carbon sheets are being retained.

It will be understood that I desire to comprehend within my invention such modifications as come within the scope of the claims and the invention.

Having thus fully described my invention, what I claim as new and desire to secure by Letters Patent is:

1. In a business machine for handling continuous form stationery and carbon sheets therebetween, the combination of a support frame mounted on a movable part of the business machine, a paper supporting frame pivotally mounted on said support frame, pivoted carbon detaining means mounted on said pivoted frame, means connecting said carbon detaining means to said support frame, and means for raising and lowering said pivoted frame thereby simultaneously actuating said detaining means.

2. In a business machine for handling continuous form stationery and carbon sheets therebetween, the combination of a support frame mounted on a movable part of the business machine, a paper supporting frame pivotally mounted on said support frame, pivoted carbon detaining means mounted on said pivoted frame, means connecting said carbon detaining means to said support frame, means for raising and lowering said pivoted frame thereby simultaneously actuating said locking means, and guiding means on the support frame and the pivoted frame for

guiding and aligning movement of continuous paper sheets and interleaved carbons so as to present said sheets and carbons into writing and detaining positions.

3. In a business machine for handling continuous form stationery, the combination of a platen and carriage, a frame mounted on said carriage comprising end plates, an interconnecting plate and a guide, a U-shaped pivoted frame mounted on said end plates having a roller mounted on one end thereof with adjacent guides, pivoted hooks on said frame and means attached to said end plates for actuating said hooks as the pivoted frame is raised and lowered, and means of raising and lowering said pivoted frame.

4. In a business machine for handling continuous form stationery having sheets of carbon disposed therebetween for movement with respect to the stationery for reproducing plural forms upon adjacent form faces on the stationery comprising in combination, a supporting frame adapted to be carried upon a movable part of the business machine and movable therewith, a paper sheet supporting frame having means pivotally mounting the same upon said support frame, hook means pivotally mounted upon said paper sheet supporting frame for engaging carbon carriers which carry carbon sheets to detain the same from forward movement, means extending from said hook means into engagement with said support frame for causing movement of said hook means upon pivotal movement upon said paper support frame to engage the carbon sheet carriers and detain the sheets upon elevation of said paper support frame and disengage the carbon sheet carriers and release the sheets upon lowering of the same, and means for moving said paper support frame.

5. In a business machine for handling continuous form stationery having sheets of carbon disposed therebetween for movement with respect to the stationery for reproducing plural forms upon adjacent form faces on the stationery comprising in combination, a supporting frame adapted to be carried upon a movable part of the business machine and movable therewith, a paper sheet supporting frame having means pivotally mounting the same upon said support

frame, hook means pivotally mounted upon said paper sheet supporting frame for engaging carbon carriers which carry carbon sheets to detain the same from forward movement, means extending from said hook means into engagement with said support frame for causing movement of said hook means upon pivotal movement upon said paper support frame to engage the carbon sheet carriers and detain the carbon sheets upon elevation of said paper support frame and disengage the carbon sheet carriers upon lowering of the same, and means for moving said paper support frame, said last mentioned means including a toggle link to retain said paper support frame in the upward position.

6. In a business machine for handling continuous form stationery and interleaved carbon sheets, the combination of a pivoted supporting frame constructed and arranged for vertical swinging movement with respect to the business machine upon which it is carried, means for mounting said frame upon a movable portion of said business machine to move with it, and carbon arresting means comprising a pivoted member mounted on said pivoted frame and actuated by movement of said frame to arrest forward movement of carbon sheets located between continuous paper sheets upon upward movement of said frame.

7. In a business machine for handling continuous form stationery and interleaved carbon sheets, the combination of a pivoted supporting and guiding frame constructed and arranged for vertical swinging movement with respect to the business machine upon which it is carried, means for supporting said frame on a movable portion of said business machine to move with it, carbon arresting means comprising a member mounted for swinging movements on said pivoted frame actuated by movement of said frame to arrest forward movement of carbon sheets located between continuous paper sheets upon upward movement of said frame, and means for simultaneously elevating said pivoted frame and actuating said arresting means and of lowering said frame and moving the arresting means to an inoperative position.

WILLIAM C. PFEIFFER.
